UNITED STATES PATENT OFFICE.

JOSEPH S. AMUSSEN, OF LOS ANGELES, CALIFORNIA.

DEVICE FOR SUPPORTING AND ROCKING PATIENTS.

Application filed August 29, 1922. Serial No. 584,989.

To all whom it may concern:

Be it known that JOSEPH S. AMUSSEN, a citizen of the United States, residing at Los Angeles, in the county of Los Angeles and State of California, has invented certain new and useful Improvements in Devices for Supporting and Rocking Patients, of which the following is a specification.

My invention relates to osteopathic apparatus, and is a device adapted for supporting, and rocking the patient.

An important object of the invention is to provide a device of the above mentioned character, so constructed that the practitioner may rock the patient, thus giving motion to the spine, while it is being treated.

A further object of the invention is to provide a device of the above mentioned character, which is simple in construction, convenient and easy to operate, and comfortable to the patient.

Other objects and advantages of the invention will be apparent during the course of the following description.

In the accompanying drawings forming a part of this specification and in which like numerals are employed to designate like parts throughout the same,

Fig. 1 is a side elevation of a device embodying the invention, showing the same in use,

Fig. 2 is a perspective view of the frame embodied in the device,

Fig. 3 is a similar view of the supporting element or pad of the device, parts broken away,

Fig. 4 is an enlarged elevation of the complete device,

Fig. 5 is a detail section taken on line 5—5 of Fig. 4,

Fig. 6 is a fragmentary side elevation of the frame, parts in section,

Fig. 7 is a side elevation of the complete device,

Fig. 8 is a detail section taken on line 8—8 of Fig. 7; and,

Fig. 9 is a plan view of straps and associated elements which support the pad.

In the drawings, wherein for the purpose of illustration is shown a preferred embodiment of my invention, the numeral 10 designates a rocking element or frame, as a whole. This rocking element embodies longitudinally curved elements 11, preferably in the form of tubes, to afford strength and lightness. The tubes are preferably con-

nected between their ends by transverse bars 12, secured thereto by screws 13 or the like, Figure 8. The free ends of the curved elements or tube 11 are rigidly connected by 60 cross heads 14, having depending shanks 15, Figure 6, projecting into the ends of the tubes 11, and secured thereto by screws 16 or the like. The cross heads are equipped with handles 17, as shown. The cross heads 65 14 are provided with elongated slots 18, preferably extending longitudinally of the elements 11, as shown.

The numeral 18' designates a flexible supporting element or pad, which may be made 70 of suitably strong material. This pad may embody a casing 19, having a filling 20, of cotton or the like. At each end of the supporting element is a loop 21, formed of any suitably strong material, such as canvas or 75 the like. This loop is secured to the ends of straps 22', by rivets 22 or the like, Figures 3 and 9. The numeral 23 designates a strap, secured to the outer surface of the end of the pad casing 19, and extending 80 transversely thereof, as shown.

The loop 21 carries a coupling 24, preferably made of metal, and provided with a stud 25, which is T-shaped, and adapted to be passed through the slot 18, when parallel 85 therewith. When turned to a position at right angles to this slot, the stud will securely lock the coupling 24 to the cross head 14, as shown.

As clearly shown in Figure 7, the supporting element 18', is held within the rocking frame, and is shorter than the same, and hence spaced therefrom. The studs 25 are securely held within the slots 18, and the straps 22' carried by the loops 21, support 95 the load of the patient. These straps extend longitudinally within the casing 19, upon the rear side of the filling 20, and project through openings in the end of such rear side. The transverse straps 23 have their 100 ends passed about the reduced lower portions of the handles 17, and serve to bind the ends of the pads 18', to these handles, holding the same thereto, in close relation. The ends of the straps 23 are connected by buckles 26. 105

In the use of the device, the patient may lie with his face down, with the device beneath the abdomen, near and slightly in advance of the hips. The practitioner may hold one of the handles in one hand, and 110 rock the patient, while he employs the other hand in treating the spine, and in this man-

ner, the spine is given motion while being treated.

It is to be understood that the form of my invention herewith shown and described is to be taken as a preferred example of the same, and that various changes in the size, shape, and arrangement of parts may be resorted to without departing from the spirit of my invention.

Having thus described my invention, I claim:

1. A device for supporting and turning a patient, comprising a curved rocking frame adapted to be arranged beneath the patient, the upper side of the frame being open when in use so that the body of the patient is received therein, the rocking frame being mounted upon a table or the like beneath the body of the patient, the major portion of 20 the body also resting upon the table.

2. A device for supporting and turning a patient, comprising a curved substantially rigid rocking member adapted to be arranged beneath a patient and to extend transversely thereof, the upper side of the 25 rocking member being open so that the body of the patient is received therein, the rocking member projecting above the patient.

3. A device for supporting and turning a patient, comprising a curved substantially rigid member adapted to be arranged beneath the patient and having its upper side open, a substantially flexible supporting element arranged within the curved member 35 and connected therewith, and a handle connected with one end of the curved member.

4. A device for supporting and turning a patient, comprising a curved rocking member having its upper side permanently open 40 for the reception of the body of the patient, and a supporting element arranged within the curved rocking member and connected with the ends of the rocking member.

5. A device for supporting and turning a patient, comprising a curved substantially rigid rocking frame provided upon its upper side with a recess for receiving the body of the patient and provided at its ends with handles, and a pad within the frame. 45

6. A device for supporting and turning a patient, comprising a curved rocking frame, a pair of couplings detachably connected with the ends of the frame, straps connected with the couplings, and a pad supported by 50 the straps. 55

7. A device for supporting and turning a patient comprising, a support member having a curved lower rocking face to rest upon a table or the like, the support member being arranged beneath the body of the patient with the major portion of such body resting upon the table which carries the support member, and handles secured to the ends of the support member and extending upwardly approximately above the said body. 60 65

8. A device for supporting and turning a patient comprising, a curved support member having a lower convex rocking surface and an upper concave surface forming a recess for the reception of the body of the patient, the support member being relatively narrow to permit of the major portion of the body of the patient resting upon a table or the like upon which the support member is 70 also mounted. 75

9. A device for supporting and turning a patient, comprising a support member having a lower curved rocking face to turn upon a table or the like, said support member having a recess upon its upper side for receiving the body of the patient whereby the major portion of such body may rest upon the table or the like upon which the support member is also mounted. 80

In testimony whereof I affix my signature.
JOSEPH S. AMUSSEN.
